UNITED STATES PATENT OFFICE.

PAUL G. BOGDANOFF, OF BATTLE CREEK, MICHIGAN

VACUUM PUMP.

Application filed December 27, 1919. Serial No. 347,721.

To all whom it may concern:

Be it known that I, PAUL G. BOGDANOFF, a citizen of the United States, residing at Battle Creek, in the county of Calhoun and State of Michigan, have invented certain new and useful Improvements in Vacuum Pumps; and I hereby declare that the following is a full, clear, and exact description thereof, reference being had to the accompanying drawings, which form part of this specification.

This invention is a novel rotary pump especially intended for producing and maintaining a partial vacuum or suction in apparatus (such, for instance, as heating apparatus, etc. in which it is desired to produce a partial vacuum by suction applied to the outlet of the apparatus); but the pump is also adapted for forcing gases into apparatus wherein compression of gases may be desired.

The invention has particular reference to the construction of the pump; and is capable of embodiment either in a multistage pump, or a single stage pump, according to the capacity of the apparatus, and the amount of suction, or compression, which it is desired to produce thereby.

I will first explain the invention with reference to the accompanying drawings in which I have illustrated forms of pumps embodying the invention and then set forth in the claims the essentials of the invention, and the novel features of construction, and novel combinations of parts, for all of which protection is desired.

In said drawings Fig. 1 is a longitudinal sectional view of a multi-stage pump embodying the invention.

Fig. 2 is a front elevation of the pump shown in Fig. 1.

Fig. 3 is a longitudinal sectional elevation of a single-stage pump embodying the invention.

Fig. 4 is a front elevation of the pump shown in Fig. 3.

Fig. 5 is an enlarged face view of the primary impeller partly broken away.

Fig. 6 is a longitudinal sectional view of such impeller.

Fig. 7 is a detail view of one of the annular plates detached.

Fig. 8 is a section on the line 8—8, Fig. 7.

Fig. 9 is a section on the line 9—9, Fig. 7.

Figs. 10 and 11 are detail views illustrating the slot in the adjusting ring.

The main casing of the pump is approximately circular in end elevation. (See Figs. 2 and 4.) As shown it is formed with an axially disposed circular fluid supply chamber A in which is located the primary impeller 1.

Surrounding the chamber A and concentric therewith is an annular suction chamber B, in which are located opposed annular plates 2, hereinafter referred to, between which plates the water is radially discharged into a third annular primary discharge chamber C, concentric with and circumferentially surrounding the chamber B, so that the fluid ejected by the impeller between the plates 2 is directed into chamber C. From chamber C the fluid is conducted inwardly by radially disposed ports or passages E back toward a second axially disposed secondary fluid chamber F, beside and in axial alignment with chamber A. In chamber F is a step-up impeller 5, which discharges the fluid into a secondary discharge chamber G concentric with and surrounding chamber F.

Fluid is admitted into chamber A through a laterally disposed inlet port a in the wall of the casing; gaseous fluid may be admitted into the suction chamber B through a port b in the side wall of the casing, as shown, and the fluid mixture is discharged from the chamber G through an outlet port g.

Fluid such as water is admitted through the port a into the chamber A and ejected by the impeller 1 through the suction gap between the nozzle plates 2 into the chamber C and in so doing the fluid in chamber B, which may be water or gases, or mixtures thereof, is drawn through the apertures in the plates 2 and injected into the chamber C by the action of the impeller 1 and plates 2; and the mixed fluid and gases pass through passages E to the second impeller 5 and are discharged thereby with increased pressure into the chamber G, from which they escape through the outlet g to the desired point of discharge or utilization.

The ports a, b, and one-half of chambers A, B, and C, may be formed in one longitudinal half of a main casing casting; and the other half of chambers A, B, and C, may be formed in the opposed, or central, portion of the main casing; as shown in Figs. 1 and 3 of the drawings; and the chambers F, G and outlet port g may be formed in a third section of the main casing

casting, as indicated in Fig. 1 of the drawings.

Extending axially through the chambers A, F, which are in axial alinement, is a main shaft S; and on this shaft within the chamber A is mounted the primary impeller 1; which may be fixedly secured to the shaft in any suitable manner, and is shown as clamped thereon between screw collars or nuts 8.

The impeller 1 is preferably composed of a disk-like body portion having a hub 1^a and a radial web portion 1^b; and an opposed annular disk portion 1^c, which is bolted to the face of the portion 1^b (see Figs. 5 and 6) as shown. The annular portion 1^c is preferably cast with a plurality of curved spaced ribs 1^f on its inner face the spaces between the ribs forming con- volutely curved channels 1^e, which channels convolutely converge toward the center of the impeller and are shaped as shown in Figs. 5 and 6 so that the water will be discharged through these channels into an annular nozzle passage 1^p at the periphery of the impeller. When the impeller is rapidly rotated water will be discharged through this passage 1^p from the periphery of the impeller in an annular sheet of the desired thickness and in a plane perpendicularly to the impeller axis. The peculiar design and form of the vanes of the impeller ensures the efficient rapid discharge of water in an annular sheet or stream from and beyond the periphery of the impeller.

The outer face of the ribs 1^f may be dressed to make a close fit against the opposed dressed face of the web portion 1^b of the impeller; and these parts 1^a, 1^b may be united by means of bolts or screws 1^g, the heads of which bolts can be countersunk in the web portion 1^b, as shown in Fig. 6, while the threaded portions of the bolts engage threaded apertures in the rib 1^f.

The impeller may also be provided near its periphery with exterior annular grooves 1^h, which may be suitably packed if desired, to make a close running joint between the sides of the impeller and the opposed portions of the division wall between the chambers A and B.

The shaft S may be rotated by any suitable means. When rotated at proper speed water or like fluid will be forcibly discharged from the periphery of the impeller in practically a continuous circumferential annular sheet into and through the narrow annular space between the opposed plates 2 in chamber B. These plates 2 are alike but oppositely disposed. Each plate 2 has a plurality of circumferentially disposed section apertures 2^a; two concentric annular series of such apertures being shown. These apertures are preferably inclined at an

angle of approximately 65° to the axis of the shaft S and are directed outwardly from the chamber B so that the water forcibly discharged between the annular plates past the apertures 2^a will create suction in such apertures and draw the fluid and gases from the chamber B through the apertures 2^a and discharge same into the chamber C.

The opposed inner sides or faces of the annular plates are preferably smooth, but their outer faces may be annularly stepped as shown at 2^b to facilitate the boring of the jet passages 2^a therein.

The plates 2 may be secured in position with in the chamber B by any suitable means. Preferably the plates 2 are secured by means of bolts 2^c, tapped into these plates and extending through suitable bores in the casing to the outside thereof, where they are secured by means of cap-nuts 2^d.

To adjustably position the plates 2 I preferably interpose between these plates and the side walls of the chamber B adjustable rings 3. These rings 3 are fitted to the outer faces of the plates 2 and can be adjusted axially by means of bolts 3^a having on their inner ends heads 3^d, which loosely engage with radially disposed key slots 3^e in the adjusting rings 3 (see Figs. 10 and 11), and these bolts are tapped through openings 3^a in the walls of the casing. By turning bolts 3^a the rings can be adjusted endwise, or longitudinally of the shaft S, to hold the plates 2 the desired distance apart; and when they are properly adjusted the bolts 3^a may be locked in adjusted position by means of cap nuts 3^f on their outer ends. As shown the heads 3^d of the bolts 3^a may be slotted for the engagement of a screw-driver, and their outer ends may be squared as indicated at 3^f for engagement of a wrench when the cap bolts 3^f are removed. When the rings are properly adjusted the nozzle plates are firmly clamped in place by tightening nuts 2^d.

Preferably a round rubber gasket 3^v is interposed between the ring 3 and the nozzle plates as indicated in Figure 8, the object of using two rings instead of one with the round gasket is to make a positively air and water tight joint to prevent leakage between the discharge and vacuum chambers.

Mounted on the shaft S within the chamber G, as shown in Fig. 1 is a second impeller 5, which may be constructed like impeller 1, if desired; but is shown as an ordinary impeller provided with radially disposed channels 5^a by which the fluid mixture is drawn from chamber F and discharged into chamber G.

The shaft S may be mounted in bearings of any suitable construction. As shown it is mounted in bearings J supported on brackets K attached to the outer end of the casing as shown. Suitable stuffing boxes L

and M are provided around shaft S at the outer sides of the chambers A and F, as shown. A suitable stuffing box or packing as N should be provided between the shaft 5 S and inner wall of chamber A. A suitable packing ring may also be provided between the hub of the impeller 1 and the wall of the chamber A, as shown at O. Packing rings may be provided between the hub of 10 the impeller 5 and the inner walls of the chamber G, as shown at P, R to prevent leakage around the impeller and between chambers F and G.

In the single stage pump shown in Figs. 15 3 and 4, the construction is substantially the same as that described, similar parts being similarly lettered; but in this latter pump the passages E are omitted, and the chamber C is provided with an outlet port e, 20 which takes the place of the discharge port g and may be similarly connected to the point of utilization or discharge of the gases or gaseous mixture.

25 Operation.

The inlet port b to the chamber B is connected with the apparatus in which a partial vacuum, reduced pressure, or suction is 20 to be maintained.

The shaft S may be driven at the desired speed by any suitable means, preferably a direct-connected automatically controlled electric motor attached to the shaft. When 35 the shaft is properly driven water is drawn in through port a and is thrown from the periphery of the impeller at a high velocity in an annular sheet between the surrounding annular plates. The absolute velocity of 40 the sheet of water passing between the said annular plates tends to create a partial vacuum in the gaps between the inner edges of the plates and the periphery of the impeller, and also in chamber B through the 45 suction produced through apertures 2^a in the plates. At the inner sides of and between the annular plates water is supplied at a high velocity; at their outer side air and water or vapor is supplied from the 50 chamber B and apparatus connected therewith on which vacuum is to be maintained. The water and air thus exhausted from chamber B are mixed with the water discharged from the impeller and discharged 55 either direct from the outlet e of chamber C in the single stage construction (Figs. 3 and 4); or through passages E into the second impeller 5 in the two stage construction 60 (Figs. 1 and 2) and discharged by the latter with increased pressure into the chamber G and escape thence through outlet g. The two stage construction is used to advantage where the mixture is to be discharged into a boiler or other apparatus

against pressure, or where it is desired to 65 pump water to a required head.

The quantity of water pumped or passed through chamber A can be determined by the speed of the impeller; its diameter; and the width of the opening between the opposed annular plates. The capacity of the 70 impeller can be readily regulated or decreased by increasing or diminishing the thickness of ribs 1^f thereby varying the cross sectional area of the channel 1^e.

75 It will be seen that the primary impeller practically rotates in the vacuum chamber B but is separated from it by the perforated nozzle plates 2. The high absolute velocity of the water discharged from the impeller 80 between the cheeks of the projecting annular plates produces, as stated, a suction or vacuum in the gap and through the perforated annular plates.

These annular plates can be fitted and adjusted to have very close clearance in the 85 gap, and also between the sides of the sheet of water discharged from the impeller and the cheeks of the plates.

Where a very high vacuum is desired the 90 suction of the impeller 5 of the two-stage pump ensures a quick removal of the mixture from chamber C, and assists in maintaining a high velocity of the fluid mixture discharged between the annular plates.

95 The pump can be primed like an ordinary centrifugal pump; and is absolute in its action, and does not need any means of starting vacuum or any assistance in any way. The pump can be connected to a well 100 and primed by means of a foot valve from the discharge side; or primed direct from the well by means of an ejector.

105 As soon as the pump is started it creates immediate suction or vacuum in the vacuum chamber B no matter if the same is at the outset filled with water or not. The mixture of water and air can be discharged by the second stage pump to a tank, cooling tower, or any other desired place.

110 When applied to low pressure heating systems the inlet port of chamber A may be connected to the receiving tank and so make the pump self-priming, and the inlet to chamber B connected to the return pipe or 115 header of the heating system. In case there is not sufficient return of condensed water from the heating coils, water from the discharge of chamber C can be by-passed into the receiving tank, to supply the necessary 120 liquid to maintain vacuum on the line.

125 In case the pump is to be used as a compressor the discharge from the pump may be conducted to an enclosed air separating tank, and the water in the tank be returned through a by-pass pipe to the chamber A and used over and over again in the pump, while the air discharged into the separating

4
tank can be conducted through a discharge in the top of tank to any desired place of use.

What I claim is:

5. 1. In a vacuum pump; a casing having a central fluid chamber having an inlet for fluid; a suction chamber surrounding the fluid chamber having an inlet for gaseous fluids; and a discharge chamber surrounding the suction chamber having an outlet; a rotary impeller mounted in the fluid chamber extending into the suction chamber; oppositely disposed relatively adjustable annular perforated plates within the suction chamber forming between them a suction gap through which the fluid discharged from the impeller passes into the discharge chamber; and means for relatively adjusting the said annular plates in said suction chamber to regulate the width of the suction gap.

2. In a vacuum pump, a casing having a fluid supply chamber provided with an inlet; an annular suction chamber surrounding the fluid supply chamber; an annular discharge chamber surrounding the suction chamber; a pair of oppositely disposed annular plates within the suction chamber forming between them a suction gap and provided with inclined apertures leading from the suction chamber to said gap; a rotary impeller mounted within the fluid chamber and discharging into the gap between the annular plates in the fluid chamber; a shaft extending axially through said chambers upon which the said impeller is mounted and whereby it may be rotated; rings within the suction chamber exterior to the annular plates; and means for adjusting the rings and said plates to vary the width of the suction gap between the plates.

3. In a rotary pump, a casing having a primary fluid chamber, a primary suction chamber surrounding the primary fluid chamber, and a primary discharge chamber surrounding the primary suction chamber; a primary rotary impeller mounted within the primary fluid chamber and discharging through the primary suction chamber; oppositely disposed annular plates within the primary suction chamber provided with inclined perforations and forming between them a suction gap through which the fluid discharged from the primary impeller passes into the primary discharge chamber, said plates being adjustable for regulating the width of the suction gap therebetween; a secondary fluid chamber at one side of the primary fluid chamber and in axial alignment therewith; passages leading from the primary discharge chamber into this secondary fluid chamber; and a secondary discharge chamber surrounding the secondary fluid chamber; and a secondary impeller in the secondary fluid chamber and discharg-

ing into the secondary discharge chamber, substantially as described.

4. In a vacuum pump, a casing having a primary fluid supply chamber provided with an inlet; an annular primary suction chamber surrounding the primary fluid supply chamber; an annular primary discharge chamber surrounding the primary suction chamber; a pair of oppositely disposed annular plates within the primary suction chamber forming between them a suction gap opening into the primary discharge chamber and provided with inclined apertures leading from the primary suction chamber to said gap; adjusting rings within the primary suction chamber exterior to the said plates; and means for adjusting the plates and rings to vary the width of the suction gap between the nozzle plates; a primary rotary impeller mounted within the primary fluid chamber and discharging into the suction gap between the plates; a secondary fluid chamber at one side of the primary fluid chamber and in axial alignment therewith; passages leading from the primary discharge chamber into this secondary fluid chamber; a secondary discharge chamber surrounding the secondary fluid chamber; a secondary impeller in the secondary fluid chamber and discharging into the secondary discharge chamber; and a shaft extending axially through said chambers upon which the said primary and secondary impellers are mounted; substantially as described.

5. In a pump of the character described, a suction chamber; opposite plates in said chamber adapted to form an annular suction gap between them, and each provided with a plurality of circumferentially disposed suction apertures inclined to the axis of the plates; with adjustable bolts passed through the side walls of the chamber and engaging said plates to adjust and secure them in position in the chamber, substantially as described.

6. In a pump of the character described, a suction chamber; opposite plates in said chamber adapted to form an annular suction gap between them; adjustable rings at the outer sides of said plates to secure them in position, said rings having slots; and adjusting bolts tapped through the walls of the chamber and having heads engaging said bolts, substantially as described.

7. In a pump of the character described, a suction chamber; opposite plates in said chamber adapted to form an annular suction gap between them and each provided with a plurality of circumferentially disposed suction apertures inclined to the axis of the plates; with adjustable rings fitted to the outer sides of said plates and adapted to secure them in position, said rings having slots; and adjusting bolts having heads

engaging said slots whereby the rings may be adjusted, substantially as described.

8. In a pump of the character specified having a suction chamber; an impeller discharging through said chamber; oppositely disposed annular plates arranged within said chamber adapted to form an annular suction gap between them and provided with a plurality of circumferentially disposed suction apertures inclined to the axis of the plates; adjustable rings fitted to the outer sides of said nozzle plates having slots; bolts tapped through the walls of the chamber and having heads engaging the slots in the rings; and setting bolts connected with the plates and extending through the walls of the chamber, substantially as described.

9. In a vacuum pump; a casing having a central fluid chamber having an inlet for fluid; a suction chamber surrounding the fluid chamber having an inlet for gaseous fluids; and a discharge chamber surrounding the suction chamber having an outlet; a rotary impeller mounted in the fluid chamber extending into the suction chamber; oppositely disposed annular

plates within the suction chamber forming between them a suction gap through which the fluid discharged from the impeller passes into the discharge chamber; the said annular plates being adjustable for regulating the width of the suction gap.

10. In a vacuum pump, a casing having a fluid supply chamber provided with an inlet; an annular suction chamber surrounding the fluid supply chamber; an annular discharge chamber surrounding the suction chamber; a pair of oppositely disposed annular plates within the suction chamber forming between them a suction gap; a rotary impeller mounted within the fluid chamber and discharging into the gap between the annular plates in the fluid chamber; a shaft extending axially through said chambers upon which the said impeller is mounted and whereby it may be rotated; said plates being independently adjustable for regulating the width of the suction gap.

In testimony that I claim the foregoing as my own, I affix my signature:

PAUL G. BOGDANOFF.
